UNITED STATES PATENT OFFICE.

HERMAN W. PAULUS, OF RICHMOND HILL, NEW YORK, ASSIGNOR TO ROYAL BAKING POWDER COMPANY, A CORPORATION OF NEW JERSEY.

APPARATUS FOR EFFECTING CHEMICAL REACTIONS.

1,420,211.

Specification of Letters Patent. Patented June 20, 1922.

Application filed July 26, 1920. Serial No. 399,083.

To all whom it may concern:

Be it known that I, HERMAN W. PAULUS, a citizen of the United States, and a resident of Richmond Hill, in the county of 5 Queens and State of New York, have invented certain new and useful Improvements in Apparatus for Effecting Chemical Reactions, of which the following is a specification.

10 The invention relates to apparatus for effecting chemical reactions by means of amalgams.

The object of the invention is to reorganize the construction and arrangement of 15 parts of apparatus adapted for effecting chemical reactions, such as reductions, by means of amalgams, to the end that such reactions may be accomplished more effectively and more economically than is possible with 20 the apparatus heretofore used for the purpose. With this object in view, the invention consists in certain novel improvements, constructions and arrangements, the advantages of which in securing the more effective 25 and economical chemical reactions by means of amalgams will be pointed out as the description of the invention proceeds.

The preferred form of the invention is illustrated in the accompanying drawings in 30 which Fig. 1 is a plan on a reduced scale of the improved apparatus for effecting chemical reactions by means of amalgams; Fig. 2 is a side elevation, partly in section, of the electrolytic cell; Figs. 3 and 4 are transverse 35 sectional views taken through the electrolytic cell and the amalgam cooling trough at different points; Fig. 5 is a transverse section taken across the reduction chamber showing the mercury pump in front elevation; Fig. 6 is a partial longitudinal section 40 of the forward end of the reduction chamber; Fig. 7 is a section taken on the line 7—7 of Fig. 8; Fig. 8 is a section taken on the line 8—8 of Fig. 7; Fig. 9 is a vertical 45 longitudinal section through the amalgam cooling trough, the middle section being broken away; Fig. 10 is a plan of the parts shown in Fig. 9 with the covers removed; Fig. 11 is a diagrammatic representation of 50 the apparatus with its accessory tanks and pumps for securing a continuous circulation of the electrolyte and the compound undergoing treatment.

The apparatus illustrated in the drawings

is adapted for effecting many kinds of chemical reactions in which an amalgam is employed. For the purpose of illustrating the principles of the invention, however, and to simplify the description, the apparatus shown is described as employed for effecting 55 the reduction or conversion of oxalic acid and its compounds into the compounds of glyoxylic acid. The apparatus comprises an electrolytic cell 15 in which the amalgam is formed; a reduction chamber 16 in which 60 the amalgam reacts with the compounds in the chamber to bring about the desired results; a mercury lift or pump 17 by which the mercury freed from the amalgam is lifted or pumped back into the electrolytic 65 cell; and a refrigerator or amalgam cooling trough 18 through which the amalgam passes from the electrolytic cell to the reduction chamber in order that it may be sufficiently 70 cool when it enters the reduction chamber. 75

In order that there may be a circulation of pregnant electrolyte through the electrolytic cell 15 the cell may be connected with a tank 19 for containing the crystallized salts of the metal to be used for the amalgam. Sodium is taken for the sake of illustration. The sodium chloride crystals are placed in the tank 19 to maintain the solution in concentrated or pregnant condition and the pump 20 raises the solution through 80 the pipe 21 whence it passes into the elevated end of the cell 15. The cell being arranged at an incline, the sodium chloride solution, which may now be termed the electrolyte, flows through the cell and the impoverished 85 electrolyte passes down the discharge pipe 22 into the tank 19 where it is again impregnated with the dissolved sodium chloride. The electrolytic action, of course, decomposes the sodium chloride into its component 90 parts, the sodium being dissolved in the mercury to form the amalgam and the chlorine passing down through the discharge pipe 22 and out through the chlorine discharge pipe 23. 100

In order that there may be a circulation of the compound undergoing treatment in the reduction chamber 16, a tank 25 is provided from which a pump 26 pumps the compound through a pipe 27 into the reduction chamber. The overflow from the reduction chamber passes through the pipe 28 back into the tank 25. The circulation of 105

the compound through the reduction chamber is continued until the desired reaction has been accomplished. In order that the operation of the apparatus may be continuous two tanks 25 may be provided. In the present instance, the chemical compound in the tanks 25 will be a mixture of oxalic acid, hydrochloric acid and water.

The electrolytic cell 15 has a cast iron bottom or plate 30, accurately machined on its upper surface 31 so that the mercury may flow in an even sheet without the formation of pools and pockets. It has been found that the flow of the mercury is facilitated by dividing the surface of the bottom 30 into separate longitudinal channels 32 (Fig. 3) by means of tile or porcelain blocks 33 inserted in longitudinally arranged pockets in the bottom 30. The number of channels 32 will, of course, depend upon the size of the cell 15 and the conditions of operation. Four channels 32 are shown. The sides 35 and the ends 36 of the cell are of concrete blocks lined with tiles 37 inserted in recesses in the bottom 30. An open framework 38 of concrete constitutes the upper edge of the cell. The parts just described are all fastened together by bolts 39, which are properly insulated by dielectric bushings. The tiles 37 constitute insulators and prevent short circuiting between the electrodes. Inasmuch as a slight suction is maintained in the cell for carrying off the chlorine gas the cell is covered with asbestos boards 40 to prevent the infiltration of air. The cell may be supported in any convenient manner as by the adjustable legs 46.

The mercury 41 acts as the cathode. The iron bottom of the cell constitutes a convenient means for conducting the negative electricity from the mercury cathode. The cathode bus bar 42 is connected with the iron bottom of the cell by means of plates 43 secured to the bottom of the cell by studs 45. The anodes may be of any suitable material and in the present instance are shown as slabs of graphite 47 resting on the tile blocks 33 and 37. Cylindrical leads 48 threaded at their lower ends screw into the anode slabs 47. The leads 48 pass through holes in a concrete beam 49 extending the length of the cell and resting on each end of the framework 38. The leads 48 are connected with an anode bus bar 51 supported from the beam 49 by means of uprights 52. The ribbons 53 form electric connections between the leads 48 and the bus bar 51. The positive current is conducted to the bus bar 51 through a lead 54.

It has been found in practice that the improved electrolytic cell described above is highly efficient in use. The combination of the iron bottom and the concrete walls permits a decrease in the thickness of the mercury film and thereby effects a saving of

that relatively expensive metal. Subdividing the cell into longitudinal channels facilitates the flow of the mercury. The mercury enters the cell through the inlet opening 56 (Fig. 2). The mercury flows through the cell between the upper surface 31 of the bottom 30 and the lower surface of the anode slabs 47. The electrolytic action caused by the passage of the electric current from the anodes to the mercury cathode splits up the sodium chloride in the cell and the sodium dissolves in the upper surface of the mercury and forms a coating of sodium amalgam thereon. The mercury and the sodium amalgam flow out of the cell through a discharge pipe 57. It will be noted that a weir 58 is provided above the opening of the discharge pipe 57. It was found by having the orifice of the discharge pipe 57 flush with the surface of the bottom 30 of the cell that the amalgam tended to back into the cell and did not flow down through the pipe 57 with the mercury. By providing the trough or weir 58 the tendency is for the amalgam to mix with the mercury as the two flow over the edge 59 of the weir and thus prevent the amalgam from backing up in the cell. This feature of construction conduces to the efficiency of the apparatus.

The electrolytic action in the cell 15 raises the temperature of the electrolyte and of the amalgam and mercury. Before the amalgam and mercury enter the reduction chamber 16 to effect the desired chemical reactions it is necessary to reduce their temperature. For this purpose they are passed through a refrigerator or amalgam cooling trough 18. The refrigerator or amalgam cooling trough is in the form of a tank 60, preferably composed of cast iron and having a double bottom forming a series of passageways 61 through which the cooling fluid flows. The cooling fluid enters the channels 61 through the inlet pipe 62 and is charged through the outlet pipe 63. The amalgam and mercury enter the tank 60 through the discharge pipe 67 from the electrolytic cell and are discharged through the pipe 64. It is thus seen that the amalgam and mercury and the cooling fluid flow in opposite direction so as to obtain the maximum cooling effect of the cooling liquor. The upper surface 66 of the bottom of the trough 60 is properly machined so as to secure the flow of the mercury in a thin sheet. It has been found desirable to provide the surface 66 with transverse slots or depressions 67 by which the flow of the mercury is assisted by preventing the formation of pools and agglomerations. The trough 60 is enclosed in a framework of wood and the whole construction is supported by bolts 67 rising from angle-irons 68 projecting outwardly from the cell 130

15. The checknuts 69 provide for the vertical adjustment of the bottom of the trough so as to give it the proper incline for the flow of the mercury therethrough. It will
 5 be understood that the amalgam cooling trough 18 is inclined in the opposite direction to the cell 15. The incline of the trough is shown exaggerated in Fig. 11. The discharge end of the trough 60 is also provided
 10 with a weir 69 so as to prevent the amalgam from building up and being retained in the trough. A series of hinged-covers 69 close the top of the trough 18 and provide ready access to its interior.

15 The cooled amalgam and mercury flow through the pipe 64 into the reduction chamber 16. The reduction chamber consists of a rectangular concrete tank lined on its bottom and sides with acid proof material 71.

20 To effect the proper contact between the amalgam and the chemical compound to be reduced, the interior of the tank is subdivided into a series of longitudinal passages or channels 72 formed by acid proof walls

25 73. In the present instance there are six channels, three of which are receiving channels and three of which are discharging channels. The amalgam and mercury enter the receiving channels 74 through inlet pipes
 30 75 connected with the pipe 64. When the amalgam and mercury enter and leave the reduction chamber they flow in the directions indicated by the arrows in Fig. 1. By causing the amalgam and mercury to flow in
 35 two directions in this manner a more compact structure is produced. By the time the mercury bearing the amalgam on its surface has passed through the inlet channels 74 and the outlet channels 76 the sodium amalgam
 40 has been acted upon by the axolic acid and hydrochloric acid solution in the chamber. The amalgam is decomposed on coming in contact with the acid thereby forming caustic soda and liberating hydrogen which in
 45 its nascent state combines with the oxalic acid solution and reduces it to sodium glyoxylate. The mercury freed from the amalgam is discharged from the reduction chamber through the outlet pipe 77 into the pipe
 50 78 whence it flows into the lower part of the mercury lift or the pump 17.

The passage of the mercury and the amalgam through the channels in the reduction chamber is effected by a series of paddle
 55 wheels 80 mounted on shafts 81 and journaled in blocks 82 mounted on the sides of the reduction chamber. There are two sets of the paddle wheels 80, one set located in the inlet channels and the other set being
 60 located in the outlet channels. These two sets of paddle wheels, as is obvious, turn in opposite directions, and for this purpose each shaft 81 is provided with a bevel gear which meshes with corresponding bevel pinion 84 secured to a shaft 85 journaled in
 65 brackets 86 secured to one side of the reduction chamber. The shaft 85 is driven from a suitable source of power. The ends of the paddles dip into depressions 88 (Fig. 6) formed in the bottom of the reduction chamber. The depressions 88 are provided so that the mercury therein is scooped out and given a proper impulse to flow in a thin sheet toward the outlet holes. At the same time that the mercury and amalgam are caused to flow through the channels in the reduction chamber the acid solution is caused to flow through the channels. The acid solution, however, being of much less specific gravity than the mercury flows much faster. This is desirable so that the free acid may act upon the amalgam to decompose it by the time it reaches the discharge openings. Moreover, a constant circulation of acid solution is maintained through the reduction chamber as described above so that the liberated hydrogen may be taken up by the constantly changing solution of oxalic acid. The reduced solution goes down through the pipe 28 and the new solution enters through pipe 27.

The bottom of the reduction chamber is below the bottom of the electrolytic cell so that the mercury must be raised from the reduction chamber into the electrolytic cell. It is well known that mercury is a difficult substance to handle properly. Where centrifugal pumps are employed for conveying mercury from one level to another the mercury has a tendency to form colloids and to subdivide into minute globules which have a tendency to float on the surface of the solution, probably because of entrained air. One of the features of the present invention is to provide a lift or pump for raising the mercury from the lower level of the reduction chamber to the higher level of the electrolytic cell with a minimum of agitation of the mercury. The construction of this mercury pump is clearly shown in Figs. 7 and 8. The pump consists of a series of buckets 90 circularly arranged on the periphery of a plate 91 provided with a hub 92 secured to a shaft 94, which is journaled in a hub 95 projecting rearwardly from the casing 96 of the drum. Each bucket 90 is provided with a narrow slot 97 opening inwardly. This slot 97 serves as an inlet orifice and an outlet orifice. The buckets 90 rotate in the direction indicated by the arrow in Fig. 7. Power is supplied by a worm gear 98 keyed to the shaft 95 and meshing with a worm 99 mounted on the shaft 85. The mercury enters the bottom of the casing 96 through the pipe 78. The level of the mercury in the reduction chamber is indicated at 100 in Fig. 7. As the revolving buckets 90 dip into the mercury in the bottom of the casing 96 the mercury flows into the buckets through the orifices 97. Inasmuch as the orifices 97 are 130

located at the end of the buckets toward the direction of travel, the mercury does not flow out until the buckets are substantially at the top. They empty or discharge into a receiving trough 101 which discharges through an opening 102 (Fig. 8) into a conduit 103 which discharges into the upper end of the electrolytic cell. Access is had to the interior of the pump through a hinged-cover 104.

The mode of operation of the improved apparatus described above for effecting chemical reactions by means of amalgams has been given in connection with the construction and operation of each of its component parts. It will be understood that the invention is not to be restricted to the form shown in the drawings, inasmuch as the principle of the invention may be embodied in other forms within the scope of the following claims.

Having thus described the invention what is claimed as new is:—

1. An apparatus for use in effecting chemical reactions by means of amalgams, comprising an electrolytic cell in which the amalgam is formed, said cell being divided into a series of longitudinal channels for facilitating the passage of the mercury therethrough, a chamber in which the chemical reaction takes place, a cooling trough between the cell and the chamber, the bottom of said trough having a series of transverse depressions to facilitate the passage of the mercury therethrough, said chamber being divided into a series of channels into some of which the mercury passes from the trough into the chamber and from some of which the mercury passes from the chamber into the cell, a series of paddles in the chamber for impelling the mercury in one direction and a second series of paddles in the chamber for impelling the mercury in the opposite direction, and means for returning the mercury from the chamber to the cell.

2. An apparatus for use in effecting chemical reactions by means of amalgams, comprising an electrolytic cell in which the amalgam is formed, said cell being divided into a series of longitudinal channels for facilitating the passage of the mercury through the cell, a chamber in which the chemical reaction takes place, means for conducting the mercury and amalgam from the cell to the chamber, said chamber being divided into a series of longitudinal channels through which the mercury and amalgam flow, said channels being arranged so that the mercury and amalgam flow in one direction through some of them and in opposite direction through others, a series of paddles in one set of channels for impelling the mercury and amalgam in one direction, a second series of paddles in the other

set of channels for impelling the mercury and amalgam in the opposite direction, and means for returning the mercury from the chamber to the cell.

3. An apparatus for use in effecting chemical reactions by means of amalgams, comprising an electrolytic cell, a reduction chamber, connections between the cell and the chamber permitting mercury to flow from the cell to the chamber, and means for lifting the mercury from the chamber into the cell, said cell being divided into a series of channels to facilitate the flow of the mercury therethrough.

4. An apparatus for use in effecting chemical reactions by means of amalgams, comprising an electrolytic cell in which the amalgam is formed, a reduction chamber in which the chemical reaction takes place by means of the amalgam, and a trough interposed between the cell and the chamber for cooling the amalgam and the mercury before they enter the reduction chamber.

5. An apparatus for use in effecting chemical reactions by means of amalgams, comprising an electrolytic cell in which the amalgam is formed, a reduction chamber in which the chemical reaction takes place and connections between the cell and the chamber, said cell being divided into a series of channels to facilitate the flow of the mercury therethrough and having at its discharge end a substantially perpendicular wall and a relatively sharp edge over which the amalgam and mercury fall to cause the amalgam and mercury to mix as they flow out of the cell.

6. An apparatus for use in effecting chemical reactions by means of amalgams, comprising an electrolytic cell in which the amalgam is formed, a chamber in which the chemical reaction takes place, and connections between the cell and the chamber, the cell being substantially rectangular in form and having at its discharge end a depression, one wall of which is substantially perpendicular and having a relatively sharp edge over which the amalgam and mercury are caused to fall so that they will mix as they flow out of the cell.

7. An apparatus for use in effecting chemical reactions by means of amalgams, comprising an electrolytic cell in which the amalgam is formed, a chamber in which the chemical reaction takes place, connections between the cell and the chamber, said chamber being divided into a series of longitudinal passages through which the mercury and amalgam flow, and means arranged within the chamber for causing the flow of the mercury and amalgam through the chamber.

8. An apparatus for use in effecting chemical reactions by means of amalgams, comprising an electrolytic cell in which the

amalgam is formed, a chamber in which the chemical reaction takes place, and connections between the cell and the chamber, said chamber being divided into a series of 5 relatively narrow channels through which the mercury and amalgams flow, said channels being arranged so that the mercury and amalgam flow in one direction through some of them and in the opposite direction 10 through others, and means for impelling the flow of the mercury and amalgam through the channels.

9. An apparatus for use in effecting chemical reactions by means of amalgams, comprising an electrolytic cell in which the amalgam is formed, a chamber in which the chemical reaction takes place, connections between the cell and the chamber, said chamber being divided into a series of channels 15 20 through which the mercury and amalgam flow, revolving paddles located in the channels for impelling the flow of the mercury and amalgam, and depressions in the bottoms of the channels below the paddles into 25 which the paddles dip.

10. An apparatus for use in effecting chemical reactions by means of amalgams, comprising an electrolytic cell in which the amalgam is formed, a chamber in which the chemical reaction takes place, connections 30 between the cell and the chamber consisting of a cooling trough by which the mercury and amalgam are cooled before entering the chamber, said trough having a metal bottom 35 with transverse grooves in the surface thereof to facilitate the flow of the mercury therethrough.

11. An apparatus for use in effecting chemical reactions by means of amalgams, 40 comprising an electrolytic cell in which the amalgam is formed, a chamber in which the chemical reaction takes place, means by which the mercury and amalgam flow from the cell into the chamber, and means by which the mercury is returned from the chamber to the cell, said last named means comprising a 45 series of rotating buckets having a single inlet and discharge opening, connections between the chamber and the buckets to fill 50 the buckets, and connections between the buckets and the cells through which the buckets discharge their contents into the cell.

12. An apparatus for use in effecting chemical reactions by means of amalgams, 55 comprising an electrolytic cell in which the amalgam is formed, a chamber in which the chemical reaction takes place, means through which the mercury and amalgam flow from the cell into the chamber and a pump for 60 raising the mercury from the chamber into the cell, said pump consisting of a series of rotating buckets arranged on the periphery of a plate, said buckets having a single aperture which serves as an inlet and an outlet, connections between the chamber and the

pump by which the mercury flows into the buckets, and connections between the cell and the pump by which the mercury flows from the buckets into the cell.

13. An apparatus for use in effecting 70 chemical reactions by means of amalgams, comprising an electrolytic cell in which the amalgam is formed, a chamber in which the chemical reaction takes place, means by which the mercury and amalgam flow from 75 the cell into the chamber, and a pump for raising the mercury from the chamber to the cell, said chamber consisting of a series of buckets arranged on the periphery of a plate, said buckets having each a single orifice arranged at its inner side, a pipe connection between the chamber and the pump having its discharge opening located above the orifices of the buckets when they are at the lowest in their rotation, and means for 80 receiving the mercury from the buckets and conducting it to the cell.

14. An apparatus for use in effecting 85 chemical reactions by means of amalgams, comprising an electrolytic cell in which the amalgam is formed, a chamber in which the chemical reaction takes place, means through 90 which the mercury and amalgam flow from the cell into the chamber, and a pump for returning the mercury from the chamber 95 into the cell, said pump consisting of a casing, connections between the chamber and the lower part of the pump casing, a series of buckets each having a single orifice, means for rotating the buckets so that they will 100 dip into the lower part of the casing, and means for conducting the mercury from the buckets to the cell.

15. An apparatus for use in effecting 105 chemical reactions by means of amalgams, comprising an electrolytic cell in which the amalgam is formed, a chamber in which the chemical reaction takes place, connections by which the mercury and amalgam flow 110 from the cell into the chamber, and a pump for returning the mercury from the chamber to the cell, said pump consisting of a casing into the lower part of which the chamber discharges the mercury, a series of buckets arranged on the periphery of a plate, means 115 for rotating the plate so that the buckets will dip into the mercury at the bottom of the casing, each bucket having on its inner side an orifice through which the mercury in the bottom of the casing passes into the 120 buckets, and a conduit between the casing and the cell into which the buckets discharge the mercury during their rotation.

16. An apparatus for use in effecting 125 chemical reactions by means of amalgams, comprising an electrolytic cell in which the chemical reaction takes place, means by which the mercury and amalgam flow from the cell into the chamber, and a pump for returning the mercury from the chamber to 130

the cell, said pump comprising a circular plate, a series of buckets arranged on the periphery of the plate, each bucket having a single orifice at its inner side, said orifice being located at the end of the bucket toward the direction in which the buckets rotate, means for rotating the plate, connections

between the chamber and the pump, and between the pump and the cell, said buckets receiving the mercury at the lowest point in their cycle of rotation and discharging it at the highest point in their cycle of rotation.

HERMAN W. PAULUS.
